FARROWING SHELTER

Marlyn Ward Reynolds, Marlyn Bevier Reynolds, and George L. Reynolds, all of Greystone Acres, Altona, Ill. 61414

Filed Apr. 25, 1966, Ser. No. 2,010

Term of patent 14 years

(Cl. D30—1)

FIG. 1 is a perspective view of a multiple-module farrowing shelter showing my new design, the canopy-doors of the confronting modules being shown as they would appear in the canopy-forming position, FIG. 1 showing the back and one side of one module and the front and opposite side of the second, identical module;

FIG. 2 is a perspective view similar to the showing of FIG. 1 but illustrating the canopy-doors raised into position for working between the modules, additionally showing the front of the second module in greater detail; and

FIG. 3 is a perspective view similar to the showing of FIG. 1 but illustrating the canopy-doors as they would appear when closing the front of the modules and showing the access doors in their position swung up to expose the interior of the modules.

We claim:

The ornamental design for a farrowing shelter, as shown and described.
